SIGNALING

Maximiliaan Julius Otto Strutt and Popko Reinder Dijksterhuis, Eindhoven, Netherlands, assignors to Radio Corporation of America, a corporation of Delaware

Application October 15, 1929, Serial No. 399,718,
and in the Netherlands October 31, 1928

2 Claims. (Cl. 250—11)

The invention relates to a method and means for transmitting wireless signals and more particularly wherein directional radiation and aerial systems are used.

5 Various experiments have proved that the strength of reception at a definite point depends on the directional effect of the transmitting aerial in a vertical plane. In one of these experiments use was made, for example, of a horizontal 10 aerial with a reflector having the shape of a parabolic cylinder; and, it was found that with two different positions of the reflector the strength of reception at a definite station to which the rays were horizontally directed, was a maximum and that between these two positions of the reflector a low minimum value of the signal 15 strength was located.

According to the invention, the insight obtained by the above mentioned experiments is made subservient to the solution of the problem of eliminating or at any rate reducing the known and dreaded fading effect.

As known, the fading effect is a phenomenon which occurs irregularly at a receiving station 25 and which probably depends on the path which the incident electromagnetic oscillations have followed in space. If the radiated oscillations reach the receiving station along two different paths, it is less probable that the reception from 30 two directions is troubled by fading. It is possible therefore to ensure a reception which is not troubled by fading by arranging some distance apart from each other two aerials which are controlled by the same transmitting installation. 35 However, due to the electrical properties of the line which connects the two aerials with the transmitting installation, it is necessary to provide a device which allows of keeping in phase the radiation of these two aerials.

40 This inconvenience does not occur with the present invention according to which two or more aerial systems controlled by the same transmitting installation are arranged in the same place in such manner that their directions of radiation 45 in a vertical plane are different.

The invention will be set forth more fully with reference to the accompanying drawing in which

Figure 1 shows diagrammatically one mode of realization of the invention.

50 Figure 2 represents an aerial of suitable shape adapted for use in the mode of realization according to the invention.

Figure 1 shows two aerials 1 and 2 which are 55 arranged in the axes of reflectors 3 and 4 respectively. These reflectors have the shape of parabolic cylinders and are arranged in such manner that the directions of radiations form different angles with the horizontal plane, said angles being chosen in such manner, that for both directions the reception is a maximum.

In order to prevent radiation in the direction of the axis of the parabolic cylinder, an aerial is used whose directional effect is normal to the longitudinal direction of the said axis. Use may be made, for example, of an aerial having a shape 65 as represented in Figure 2 which shows an aerial with which a directional effect normal to the longitudinal direction of the aerial is ensured owing to the fact that the radiation of the successive half-wave lengths are alternately utilized 70 and suppressed.

For transmitting wireless signals to diametrical point on the earth use may be made of the two paths along the earth by transmitting in opposite directions with the aid of two or more 75 aerials which are each provided with a reflector.

The use of a reflector is not essential for the invention but is desirable for long distance transmission in which otherwise the radiation in opposite directions around the globe would cause a 80 disturbing effect at the receiving station.

We claim:

1. In a system for transmitting intelligence utilizing electromagnetic wave phenomena in space, the method of eliminating electromagnetic 85 wave fading phenomena at a receiver which includes simultaneously propagating in a highly directional fashion from a plurality of spaced points, in two fixed and predetermined directions in a single vertical plane, electromagnetic wave 90 energy to a receiver.

2. A radio transmitting antenna system having, in combination, a horizontal dipole antenna, a parabolic reflector for said dipole arranged to directly propagate the energy radiated from said dipole upwardly in a direction forming a predetermined angle with the horizontal plane, a second dipole antenna spaced away from said first dipole, and a parabolic reflector for said second dipole antenna arranged to directly propagate the energy radiated from said second antenna upwardly in a direction forming a second predetermined angle with the horizontal plane, both said dipole antennæ being arranged to directly and simultaneously propagate energy in the same vertical plane, but in different directions, the angles said directions form with the horizontal plane being chosen in such manner that for both directions reception is a maximum.

MAXIMILIAAN JULIUS OTTO STRUTT.
